COMBINATION DOVETAIL AND LOCK
KEEPER

William C. Devereaux, Detroit, Mich.

Application August 30, 1935, Serial No. 38,583

1 Claim. (Cl. 16—85)

The present invention relates to door dovetails and door lock keepers, and a principal object thereof is the combination in a single structure of a dovetail and lock keeper.

5 Further objects of the present invention include the provision of a combination door dovetail and door lock keeper arranged to positively prevent relative vertical movement between a door and a supporting body; which will guide the 10 door into locking position and securely hold it from rattling when closed in such position; which is constructed entirely of non-perishable parts, thus insuring a long and efficient life; which is of relatively narrow dimensions thus adapting it for 15 use upon a relatively thin door post; and in which a minimum of resistance is offered by the unit to the closing and opening movements of the door.

It is a further object of the present invention 20 to provide a combined door dovetail and door lock keeper comprising generally a door lock keeper and a cooperating dovetail member, and a connection between them comprising one or more non-resilient but slidably supported blocks.

25 It is a further object of the present invention to provide a structure as last stated in which the door lock keeper constitutes the wedge member of a dovetail, and one or more non-resilient but slidably supported blocks are interposed between the keeper and a cooperating female dovetail member.

It is a further object of the present invention 30 to provide a construction as above stated in which the distance traveled by the blocks is less than the distance traveled by the entering lock keeper during a closing movement of the door.

It is further object of the present invention 35 to provide a construction as above stated, in which the block engaging walls of the keeper are rearwardly convergent and in which the block or blocks are complementarily formed.

40 It is a further object of the present invention to provide a construction as above stated, in which the walls of the female dovetail member are rearwardly convergent and in which the blocks are complementarily formed.

45 It is a further object of the present invention to provide a construction as above stated in which the blocks are resiliently and slidably supported upon the keeper.

50 It is a further object of the present invention to provide a combined door dovetail and door lock keeper which may be economically manufactured and readily assembled, and comprises

55 die cast lock keeper and blocks, and pressed metal cooperating dovetail parts.

Other objects and advantages of the present invention appear in the following description and in the appended claim.

In the accompanying drawing, which illustrates a preferred embodiment of the present invention and throughout the several views of which corresponding reference characters designate corresponding parts:

Fig. 1 is a diagrammatic view illustrating the application of the present invention to an automobile door and body;

Fig. 2 is a view in horizontal section taken along the line 2—2 of Fig. 1, and illustrating the 15 relation of the parts in the door closed position;

Fig. 3 is a view taken along the line 3—3 of Fig. 2;

Fig. 4 is a view in vertical section taken along the line 4—4 of Fig. 3;

Fig. 5 is a view in elevation, taken along the line 5—5 of Fig. 4; and

Fig. 6 is a fragmentary view in horizontal section taken along the line 6—6 of Fig. 4.

Considering the invention in detail, and referring to the drawing, the lock keeper 10, the outer surface of which is formed so as to provide the two spaced bolt engaging faces 12 and 14, and the intermediate sloping surfaces 16 and 18, is rigidly secured to the body frame members 22 and 24 which define a door post of the illustrative automobile body 26, by studs 20 which are threaded into bosses 21. The heads of the studs 20, as best seen in Fig. 4, are countersunk below the surface of the keeper 10. As will be understood, keeper 10 cooperates with a bolt 28, which may be associated with any conventional type of door lock, and which bears against face 12 of keeper 10, when the door is in a closed position, and similarly bears against the keeper face 14 to provide a conventional safety catch for the door. During a closing movement of the door, as will be understood, bolt 28 is cammed inwardly by the sloping surfaces 18 and 16, and is normally urged to the position illustrated in Fig. 2 by suitable spring mechanism (not shown).

As previously mentioned, lock keeper 10 also acts as a male dovetail member and for this purpose, the lateral faces 30 and 32 thereof are each formed substantially perpendicularly to the supporting surface for keeper 10, and are convergent in the direction of the closing movement of the door.

The female member of the dovetail comprises

the metal stamping 36. Dovetail 36 is formed with a substantially plane mid-section 38 and the two offset end sections 40. The mid-section 38 is channel shaped in cross section and each of the end sections are generally cup shaped in cross section and have the substantially linear inner faces 42, which are convergent from right to left as viewed in Fig. 3. Dovetail 36 is rigidly supported upon the panel 44 which forms a part of the door 46 by the studs 48, the heads of which are countersunk in openings 50 struck in the surface of the mid portion 38, and the shanks of which are threadably received in bosses 52 formed in panel 44. It will be evident, accordingly, that dovetail 36 forms a generally U-shaped housing, the legs of which are represented by surfaces 42, within which the male member or lock keeper 10 and the two cooperating sliding blocks 56 are received.

20 Each of the blocks 56, which are positioned respectively on opposite sides of keeper 10, and form a connection between keeper 10 and dovetail 36, are generally rectangular in cross section, as seen in Fig. 4. The outer surface 58 of each block 56 is complementary to and disposed for engagement by the faces 42 of dovetail 36. The inner surfaces 60 of the blocks 56 are generally complementary to the convergent faces 32 of lock keeper 10, but are curved somewhat, to permit proper action of the assembly even though the door and body are slightly out of alignment, as described in more detail hereinafter.

The blocks 56 are each supported upon, but in sliding relation to, lock keeper 10 by the pair of stamped metal elements 62 and 64. Support 62 is of a shape corresponding generally to that of lock keeper 10, and is provided with the oppositely disposed, upwardly struck lugs 66, which cooperate with corresponding recesses 68 in each of the blocks 56, to guide the movements of the latter. It will be noted that a recess 68 is cut in each side of each block 56, so that the blocks are interchangeable.

The supporting stamping 64 is formed to define a linear mid section 72, the legs 74, and the end sections 75. The legs 74 and end sections 75 support two of the faces of each of the blocks 56. The spacing between the legs 74 corresponds to the width of lock keeper 10, and the faces 74 are complementary to the faces 30 32 of keeper 10. Portions 76 of supporting member 64 are also bent around to form an enclosure for one end of each of the blocks 56, as best seen in Fig. 6. Each of the supports 62 and 64 are rigidly secured to the back of lock keeper 10 by the previously mentioned studs 20, and lie behind the shoulder 78 formed at the edge of lock keeper 10 as best seen in Figs. 2 and 5.

Each of the blocks 56 is provided with a bore 80, which receives and acts as a seat for one end of an associated compression spring 81, the other end of which is seated upon a tab 84 struck inwardly from the upwardly struck lugs 70 at the rear edge of the support 62. Tabs 70, also pass through corresponding openings in support 64 to retain the two stampings in assembled relation.

As will be understood, the springs 81 bias blocks 56 to the position illustrated in Fig. 6, in which position, each tab 66 engages one end of the guiding recess 68 formed in the corresponding block. The other extreme position of each block 56, as will be understood, is determined by the engagement of tabs 66 with the other end of the corresponding recesses 68.

75 It will be seen, accordingly, that each of the

blocks 56 is supported for sliding movement parallel to the rearwardly convergent faces 30 of lock keeper 10 between the above mentioned limits, and is supported in proper position transversely of lock keeper 10 by the supporting stamping 62 and the legs 75 of the supporting stamping 64. The compression springs 81, and the tabs 66 associated with support 62, also serve to support blocks 56 and maintain the curved faces 60 thereof in engagement with the cooperating leg sections 74 of the support 64.

With reference to the operation of the unit as a whole, a closing movement of door 46 causes dovetail 36 to move to the right with respect to lock keeper 10 and blocks 56, as viewed in Fig. 3, in which these parts are illustrated in the final or completely closed position. During the course of this movement, as previously mentioned, the lock bolt 28 is cammed inwardly along the lock keeper surfaces 18 and 16 respectively until it finally passes over the bolt engaging face 12 and finally occupies the position shown in Fig. 2. The relation of these parts is such that during the time that bolt 28 is in engagement with the sloping face 18 of lock keeper 10, the faces 42 of the dovetail 36 engage the cooperating outer surfaces 58 of the slidable blocks 56, which at the time are biased to their extreme left hand positions (Fig. 6) by the associated springs 81. Further closing movement of the door and of dovetail 36 is accompanied by a corresponding inward movement of the blocks 56, caused by the engagement just mentioned. Because of the converging character of faces 30 of lock keeper 10, however, the inward movement of block 56 is less than the movement of dovetail 36. With this arrangement, accordingly, and depending upon the degree of convergence of the faces 30, a relatively large closing movement of dovetail 36 may be accompanied by a relatively small movement of the blocks 56.

The springs 81 oppose the forward motion of the blocks 56 and maintain the faces 58 and 60 thereof continuously in engagement with the cooperating faces 42 and 74. Throughout the closing movement, accordingly, the door 46 is continuously supported in a predetermined vertical position with respect to the door post 24 by the continuous rigid support afforded by dovetail 36, blocks 56 and lock keeper 10. The dovetail connection automatically accommodates itself to wearing in of the parts, since the only effect of such wear is to modify the point in the closing movement at which the initial engagement of the parts occur. Thereafter, the action is unchanged by such wear. The operation of the unit is also unaffected by changes in the vertical positioning between the door 46 and the post 24. Any such change, it will be noted, for example a raising of door 46 with respect to post 24, simply advances the point in the closing movement at which the lower block 56 is engaged, and postpones the point in the closing movement at which the upper block 56 is engaged. After such engagement, however, the operation is as above described. The curved surfaces 60 of block 56 also accommodate the unit and provide correct operation even though the door becomes twisted with respect to post 24, thus changing the angle between faces 42 of dovetail 36 and the faces 30 of lock keeper 10. Any such twisting results merely in a partial rotation of the blocks 56 on their faces 60 with respect to the supporting surfaces 74.

In the practice of the illustrated embodiment of the present invention, the unit has been found to offer a minimum of resistance to a closing and

opening movement. The construction of the blocks 56 and of the supporting faces therefor is such that these parts move freely with respect to the other. If desired, also, an anti-friction bearing relation between the blocks and the cooperating surfaces of the parts may be provided, as disclosed in the Ball Patent No. 1,842,373, granted January 26, 1932, in which the blocks are provided with rollers, which roll along the cooperating surfaces.

It will be evident from the foregoing that the combined dovetail and lock keeper of the present invention provides, in a single unit, a device for effecting cooperation with the usual automobile door lock, and a device to positively and reliably prevent rattling of the door and prevent vertical movement thereof with respect to the supporting post. The illustrated unit, being formed entirely of relatively simple die castings, and steel stampings, may be economically manufactured. The relatively few parts promote ready assembly of the unit.

It will be evident that various changes may be made in the form, number and arrangement of parts, and accordingly, the described embodiment, while representing a preferred form of the invention, is to be regarded in an illustrative and not 5 in a limiting sense.

What is claimed is:

A dovetail wedge member comprising a combination, a base member, a second member secured to said base member and formed to define therewith a pair of recesses arranged in back-to-back relation and the bases of which recesses constitute oppositely disposed sliding surfaces, a slotted block individual to each of said surfaces and disposed to slide therealong, and means including a 10 tongue struck out of said base member individual to each block and disposed to enter the slot thereof to retain said blocks within said recesses. 15
